C. M. STROUD

OIL BURNER

Filed April 10, 1925

FIG. 1

FIG. 2

Inventor
CHARLES M. STROUD

By James, Paul & Moore
ATTORNEYS

UNITED STATES PATENT OFFICE.

CHARLES M. STROUD, OF MINNEAPOLIS, MINNESOTA, ASSIGNOR OF ONE-HALF TO
LESLIE H. FAWKES, OF MINNEAPOLIS, MINNESOTA.

OIL BURNER.

Application filed April 10, 1925. Serial No. 22,135.

The invention relates to improvements in oil burners particularly adapted for use in connection with heating plants of the ordinary construction, such as are commonly employed for heating homes and buildings, and by the use of such a heating plant may readily and quickly be converted into an efficient liquid fuel burning furnace.

The particular object of the invention is to provide an oil burner which is an improvement on the form of burners featured in my prior pending applications Serial Nos. 735,867 and 756,908 filed September 4, and December 19, 1924, respectively.

An object of the invention is to provide an oil burner of simple and inexpensive construction having an atomizing chamber or retort provided in the upper portion thereof, the bottom of which chamber is cone-shaped and has an orifice provided in the apex thereof through which the liquid fuel is delivered to the chamber, and said chamber also having a series of annular grooves provided in the cone-shaped bottom thereof, which are separated by raised ridges over which the liquid fuel must flow from one groove to the next until it reaches a series of discharge apertures through which the thus partially atomized fuel is discharged into a vaporizing and mixing chamber for admixture with air.

A further object of the invention is to provide such an oil burner having an annular vaporizing and mixing chamber into which the liquid fuel is discharged in a partially vaporized state for complete vaporization and mixing with air, and said chamber having means therein for equally distributing any partially vaporized fuel entering therein, thereby causing the resultant flame from the burner to be uniform and even.

A further object is to provide an oil burner having an outwardly flared or cone-shaped air intake thereby increasing the flow of air through the burner.

Other objects of the invention will appear from the following description and the accompanying drawings and will be pointed out in the annexed claims.

In the drawings, there has been disclosed a structure designed to carry out the various objects of the invention but it is to be understood that the invention is not confined to the exact features shown, as various

changes may be made within the scope of 55 the claims which follow.

In the drawings,

Figure 1 is a vertical sectional view through the improved burner;

Figure 2 is a sectional plan view on the 60 line 2—2 of Figure 1 with a portion of the burner broken away.

The novel oil burner featured in this invention preferably comprises an outwardly flared or cone-shaped air intake pipe 3 having a foot 4 provided on the lower portion thereof whereby it may be conveniently secured to a base plate 5 or to the floor. An elbow 6 is secured to the reduced end portion 7 of the intake pipe 3. This elbow 70 preferably has an upright pipe section or cylinder 8 secured thereto by means of threads 9. The elbow 6 may be conveniently supported upon a pedestal or support comprised of a T-fitting 11 having its lower end 75 secured to a floor plate 12 by means of a threaded nipple 13. A reducing bushing 14 is preferably provided in the side outlet of the T-fitting and an oil feed pipe 15 has one end secured to this bushing as clearly shown 80 in Figure 1. A pipe section 16 is mounted in the upper outlet of the T-fitting 11 and upwardly extends through an aperture in the lower portion of the elbow 6. A boss 17 is preferably provided on the elbow 6 in 85 order to provide a seat for a spacing collar 18 mounted upon the upright pipe section 16 and having its lower end resting upon the upper face of the T-fitting 11. This spacing collar 18 functions to provide a connecting means between the lower face of the hub 17 and the T-fitting 11 to carry the weight of the elbow 6 and the adjacent end of the air intake pipe 3. The length of this spacing collar may be varied to adjust the up- 95 right pipe section to the proper level.

A reducing coupling 19 is terminally mounted on the upright pipe section 16 and preferably has a relatively smaller pipe section 21 mounted therein which upwardly extends through the cylinder 8 and has a cone-shaped member 22 secured to the upper end thereof, above the upper end of the cylinder 8. This cone-shaped member 22 has an aperture 23 provided in the apex thereof which is in communication with the interior of the pipe section 21. A cylindrical casing 24 is preferably integrally formed with the outer

portion of the cone-shaped member 22 and extends downwardly therefrom to enclose the major portion of the cylinder 8. The diameter of the casing 24 is relatively greater than that of the cylinder 8, thereby providing an annular mixing chamber 25 around the cylinder 8 into which the partially vaporized fuel is delivered from the upper portion of the burner. The walls of the casing 24 also preferably extend upwardly to a point slightly above the apex of the cone-shaped member 22. A cover 26 is seated upon the upper end of the casing thereby providing a vaporizing chamber 27 into which the fuel oil is discharged from the oil feed pipe 21. As shown in the drawing, the upper surface of the cone-shaped member 22 preferably has formed thereon a plurality of annular grooves 28 which are separated by raised ridges 29, in distinction from the spiral or continuous groove shown in the cone member of my pending application #735867. These grooves and ridges function to atomize the liquid fuel as it flows downwardly thereover from the apex of the member 22. The grooves 28 also function to evenly distribute the flow of liquid from the orifice 23, over the entire surface of the cone-shaped member so that the fuel oil will be practically vaporized in the heating chamber 27, before entering the annular mixing chamber 25, after the burner has been started. A series of relatively small ducts or passages 31 are provided in the cone-shaped member 22, adjacent the casing wall 24, through which the vaporized or partially vaporized fuel oil is discharged into the mixing chamber 25 where it is thoroughly mixed with air supplied to the chamber through the air intake pipe 3 and the upright cylinder 8, as indicated by the arrows in Figure 1. As shown in the drawing, the ducts or passages 31 are somewhat elongated and the walls thereof will be heated to a high degree of temperature and will assist materially in vaporizing any of the fuel which may be delivered to these ducts from the annular grooves in an unvaporized condition. A suitable number of these ducts are provided adjacent the wall of the casing 24 as indicated in Figure 2 of the drawing.

A feature of this invention resides in the provision of an annular groove 32 formed in the lower portion of the casing 24. This groove functions as a means to catch any fuel oil which may flow downwardly over the inner surface of the casing wall 24 when starting the burner. Any oil entering this groove will be equally distributed around in the groove by the action of the air currents so that the flow of air through the chamber 25 will cause such oil to be downwardly blown against a corrugated surface 33 provided in the lower central portion of a priming pan or saucer-like member 34. Such ac-

tion of the air against the partially atomized fuel oil in the groove 32 will cause it to become thoroughly atomized so that it may readily be ignited. The priming pan 34 is mounted to encircle the upright cylinder 8. A spacing collar or ring 35 is preferably interposed between the lower portion thereof and the upper face of the elbow 6 to provide a supporting means therefor. The height of this ring may be varied to adjust the position of the priming pan with relation to the lower edge of the casing 24.

An upright flange 36 is preferably integrally formed in the pan 34 and functions to deflect the mixture of air and fuel oil upwardly after passage thereof downwardly and outwardly around the lower edge of the casing 24 as indicated by the arrows in Figure 1. By means of this upright flange 36 and the corrugated surface 33 in the lower portion of the priming pan, the fuel oil will be thoroughly atomized before being directed outwardly from the burner, thereby providing a highly combustible mixture which may readily be ignited when the burner is cold. After the burner has been started and the casing 24 becomes thoroughly heated, the chamber 27 at the upper portion of the burner will function as a retort or a means for preheating and vaporizing the fuel oil before it is discharged into the annular mixing chamber 25. Also as the fuel enters the mixing chamber 25 through the ducts 31, it will be blown outwardly against the heated wall of the casing 24, thereby causing it to become thoroughly vaporized and mixed with air before being discharged outwardly from beneath the lower edge of the casing 24. An oil overflow pipe 37 is preferably connected with the priming pan 34 to return any oil accumulating in the member 34 back to its source.

The construction of this novel burner is such that it may readily be used in connection with furnaces or heating plants of ordinary construction. As a result of the enlarged intake opening of the intake pipe 3, this novel burner may readily be used without the need of applying power operated means thereto for forcing air through the burner, its design being such that the natural draft of the furnace will be sufficient to supply sufficient air to the burner at all times.

I claim as my invention:

1. A liquid fuel burner comprising a priming pan having an air intake projecting above the same, a casing encircling said intake and spaced therefrom to form a mixing chamber, said casing being also spaced from said priming pan, the currents of fuel-laden air flowing downwardly through said mixing chamber under said casing and the surface of said pan being corrugated for receiving and deflecting such currents of air

and atomizing the particles of fuel suspended therein, said pan having an upwardly projecting flange encircling said casing and spaced therefrom and cooperating with said 5 corrugated surface to deflect the air currents and mix the vaporized fuel therewith.

2. A liquid fuel burner comprising a priming pan, an air intake pipe passing upwardly through the pan and supporting and 10 sealingly engaging the same, a casing encircling the pipe and spaced therefrom and from the pan to form a mixing chamber, and adapted to receive and downwardly direct the currents of air received through the 15 air pipe, a conical partition in said casing above said air pipe forming an upper vaporizing chamber for receiving the liquid fuel, said chamber having a convex bottom and said partition having a plurality of com- 20 paratively small elongated passages, the walls of which are adapted to be heated to aid in vaporizing the fuel before it is dis- charged into the mixing chamber, said pan having corrugations disposed beneath said 25 casing.

3. A liquid fuel burner comprising a priming pan, a sleeve centrally arranged

with respect thereto and projecting a consider- 30 able distance above said pan and adapted to form an air intake, a casing encircling said sleeve and spaced therefrom and from said pan and having a closed top, and means between the tops of said casing and said sleeve forming a retort within said casing whereto the liquid fuel is delivered, the 35 lower walls of said retort having ports leading therefrom to the space between said casing and sleeve, said sleeve delivering air currents to flow downwardly in the space 40 between said sleeve and casing and mingle with the vaporized fuel from said ports, the lower portion of said casing cooperating 45 with said pan to atomize and vaporize particles of liquid fuel which may be held in suspension in said air currents, said pan having a flange encircling the lower portion of said casing and spaced therefrom and operating to upwardly direct the vapor-laden air currents from between said sleeve and cas- 50 ing.

In witness whereof, I have hereunto set my hand this 6th day of April, 1925.

CHARLES M. STROUD.
